INVENTOR

Virgil Price

United States Patent Office.

VIRGIL PRICE, OF NEW YORK, N. Y.

Design No. 3,822, dated January 25, 1870.

DESIGN FOR A SCABBARD.

The Schedule referred to in these Letters Patent and making part of the same.

To all whom it may concern:

Be it known that I, VIRGIL PRICE, of the city, county, and State of New York, have invented a new and original Design for Scabbard; and I do hereby declare that the following is a full, clear, and exact description thereof, which will enable others skilled in the art to make and use the same, reference being had to the accompanying drawing, forming part of this specification, in which the drawing represents a side view of my design for scabbard.

This invention relates to a design for the upper slide of sword-scabbards, more particularly Knights' Templar sword-scabbards. The chief insignia of the order of Knights Templar are arranged on the slide.

In the drawing, there are represented on the slide the cross *a*, the shield *b*, hat *c*, sword *d*, banner *e*, fasces *f*, the scrip *g*, and flask *h*.

The various figures are in *bas-relief*. The crosses on the banner and shield, and the main cross *a*, are red, unless they are altogether omitted.

Having thus described my invention,
I claim as new, and desire to secure by Letters Patent—

The design for scabbards, as shown.

VIRGIL PRICE.
